UNITED STATES PATENT OFFICE.

EDGAR N. GOODLETT, OF SAN FRANCISCO, CALIFORNIA.

CONCRETE RAILWAY-TIE.

1,225,325.

Specification of Letters Patent.

Patented May 8, 1917.

Application filed February 3, 1916. Serial No. 75,894.

To all whom it may concern:

Be it known that I, EDGAR N. GOODLETT, a citizen of the United States, residing in the city and county of San Francisco, State 5 of California, have invented a new and useful invention—*to wit*, Improvements in Concrete Railway-Ties—of which the following is a specification.

The invention relates particularly to concrete railway ties and has among its objects the cushioning of the shock between the rail and the tie; to render the center of the tie resilient; and to prevent the ties becoming center-bound in the ballast of the 15 roadbed. Other objects and advantages will appear as the description progresses.

In the specification and the annexed drawings, I illustrate the invention in the form that I consider the best, but it is to be understood that I do not limit myself to such form, because the said invention may be embodied in other forms; and it is also to be understood that in and by the 25 claims following the description I desire to cover the invention in whatever form it may be embodied.

In the accompanying two sheets of drawings:

Figure 1 is a perspective view looking down a section of roadbed having rails supported upon ties constructed in accordance with this invention.

Fig. 2 is a fragmentary detail in cross section of a tie and insert block taken on the line II—II of Fig. 1.

Fig. 3 is a detail in perspective of an insert block.

Fig. 4 is a plan view from above showing the preferred arrangement of the reinforcing bars in the sleeper section and the modified form of connecting rods introducing a link therein.

Fig. 5 is a side elevation of the same.

In detail the structure illustrated in the drawings includes the end structures, 1—1 joined by connecting bars 2—2 embedded therein. The end section consists of a suitable mixture of concrete composed of cement, sand, gravel, and water in the proper proportions mixed and cast in suitable molds to form the end sections substantially as shown. These sections are cast around a core fixed in the mold to form the recess 3 preferably extending about two

thirds the depth of the end section. The 55 hole 5 extends from the bottom of the recess through the base of the tie. The lower portions of each section are reinforced by the longitudinal bars 6—6 beneath the recess 3 and parallel with its sides, and the 60 superimposed cross bars 7—7 extending transversely beneath the recess 3 on opposite sides of the hole 5, and adjacent thereto.

All four sides of the recess 3 taper slightly downward, and the same is true 65 of the hole 5, although not particularly important with respect to this hole 5, except to facilitate the removal of the core. The recess 3 is preferably rectangular having slightly rounded and filleted corners and 70 preferably with a flat bottom forming a shoulder or ledge around the opening 5. The end sections are preferably cast in the mold upside down, the core forming the recess 3 and the hole 5, being fixed in the 75 exact center of the mold bottom. The plastic concrete is then dumped into the mold and vibrated or tamped, the reinforcing bars 7—7 and 6—6 being placed in position at their respective levels before the mold 80 is entirely filled. The ends of the connecting bars 2—2 project into the mold and are permanently embedded in the end sections 1—1. It is advisable to cross-tie these connecting bars as at 9 to prevent them 85 from spreading and cracking the concrete if roughly handled in setting and ballasting the tie in the roadbed. The end sections 1—1 are identical in construction.

The insert blocks 10 are a very important 90 element in this invention. They taper from the top to the bottom on all four sides and are intended to exactly fit the recesses 3 snugly, with sufficient friction to permanently engage the walls of the recess without too much wedging action likely to induce fractures through the concrete structure emanating from the recess opening.

It is important that the taper of the walls of the block be parallel with the taper of 100 the walls of the recess. The depth of the block is such, that when it rests upon the bottom 8, the surface 11 will be above the surface 12 of the end section. The block is preferably made in two sections as illustrated in Fig. 2. The longitudinal division of the block enabling it to adjust itself 105 better to the recess 3. The divided block

also absorbs traffic shocks better than a single block, and also has economic advantages.

The ties are spaced in the roadbed in accordance with common practice with the exceptional advantage that the ballast can be tamped harder in the center of the roadway and left less hard around the end section to induce lateral drainage from the center of the roadbed, in contradistinction to the practice where wooden ties are used, tamping hard under the rails or under the ends of the ties and leaving the center as free as possible to prevent the ties becoming "centerbound"; this type of tamping tending to puddle the water in the center of the roadbed, resulting in the gradual undermining of the ties in wet weather with attendant danger to traffic.

The rails are laid across the ties and rest upon the surfaces 11 of the insert blocks to which they are spiked or screwed in the usual manner. It is desirable that the base of the rail be exactly centered between the ends of the end sections 1, so that the lateral supporting power of the end section is equal on both sides of the rail. The open center or gap in the tie is slightly less than the length of one end section, this distance varying slightly with the gage of the railway, the conditions of traffic thereover or other considerations. Tie plates between the rail and the tie may be omitted, except in unusual circumstances, as practice has proven that the rail embeds but slightly in the surface of the insert block if a reasonably good quality of wood is available for the insert block.

A tie with an open resilient center, an insert block tapering downwardly substantially as shown and described, eliminates most of the evils attending the use of a tie with a relatively uniform, longitudinal, cross-section as commonly used.

A wide, open center in the tie saves material and reduces first cost. A resilient open center without supporting capacity on the ballast of the roadbed prevents the tie from becoming centerbound, or "hanging up" in the center, as it is colloquially expressed. The resilient or springy center in the tie permits a certain independent vertical movement in the opposite end sections of the tie, whereby a depression of one end section does not necessarily mean upward or elevating tendency on the opposite end; lateral teetering of the tie with the center of the roadbed as a fulcrum is entirely eliminated. The use of this tie greatly reduces side rocking and wear and tear on the rolling stock passing over the railway.

Concrete as a material for railway ties is ideal except for one disadvantage, it tends to crumble when directly exposed to the heavy pounding of heavy traffic transmitted

through the rails to the tie; a secondary disadvantage is that rigidity of the concrete reacts severely upon the rolling stock. These disadvantages are entirely eliminated by the peculiar shape and the combinative action between the insert block in the recess in the tie section, interposed between the tie and the base of the rail which it directly supports. The insert blocks are forced into the recess 3 by the weight of the traffic until they rest against the bottom 8 of the recess, the compression of the wooden block exerting a lateral friction against the walls of the recess 3, easing the block in its descent into the recess, the block absorbing the shock and vibration of the passing traffic, transmitting only the dead weight to the concrete portion of the ties, which it is admirably adapted to support when relieved of the disintegrating stresses which are absorbed in the insert block. Reinforcement of the concrete is reduced to the minimum, and that is concentrated beneath the block and located adjacent to the base of the tie, to take the ultimate load on the tie and distribute it uniformly throughout the area of the base thereof, resting upon the roadbed. Owing to unequal contraction and expansion, chemical and other actions, reinforcement tends to induce fractures if indiscriminately distributed throughout the mass of concrete.

For convenience in handling and to give greater flexibility to the center of the tie, the rods 2 of the opposite end sections may be joined by the links 13—13 as illustrated in Figs. 4 and 5. This form is advantageous where labor is scarce and it is desirable to handle one end section of the tie at a time, joining and closing the links 13—13 after the opposing sections are set in the roadbed.

Having thus described my invention, I claim:

1. A railway tie including a plurality of sections joined by resilient rods and having recesses therein tapering downwardly; and tapered blocks fitting said recesses, each section being formed with a hole running from the lower face thereof to the recess therein to receive a block dislodging tool.

2. A railway tie including concrete end sections with recesses therein tapering downwardly; removable compressible blocks frictionally engaging the walls of said recesses; and rods joining said end sections each section being formed with an unobstructed hole to receive a block dislodging tool.

3. A railway tie including concrete end sections with downwardly tapering recesses therein opening in the center of the tops of said end sections; blocks fitting said recesses, and continuous resilient rods joining said end sections and embedded therein.

4. A railway tie including concrete end

sections with downwardly tapering recesses therein opening in the center of the tops of said end sections; blocks fitting said recesses, and continuous resilient joining rods embedded in the ends of said end sections. 25

5. A railway tie including concrete end sections with recesses therein tapering downwardly; pairs of blocks combined and shaped to fit said recesses and projecting 10 above said end sections; and resilient joining rods embedded in said end sections.

6. A railway tie including concrete end sections with recesses therein tapering downwardly and having openings in the 15 bottoms thereof spaced inward from the sides of said recesses; blocks frictionally engaging the walls of said recesses and normally supported slightly above the bottoms thereof; and joining rods embedded in the 20 ends of said end sections.

7. A railway tie including concrete end sections with longitudinal recesses therein tapering downwardly and having openings in the bottoms thereof spaced inward from

the walls of said recesses, said recesses opening in the longitudinal and transverse centers of said end sections; blocks fitting said recesses and extending above said end sections; and joining rods embedded in the 30 ends of said end sections.

8. A railway tie including concrete end sections spaced apart endwise a distance approximately equal to the length of one end section, resilient joining rods embedded in the ends of said end sections; longitudinal 35 recesses in said end sections and tapering downwardly; blocks fitting said recesses and extending above said end sections; transverse reinforcing bars beneath said recesses, and longitudinal reinforcing bars below said 40 transverse reinforcing bars embedded in said end sections.

In testimony whereof, I have hereunto set my hand at San Francisco, California, this 21st day of January, 1916.

EDGAR N. GOODLETT.
